L.B. Halliday
by Watson E. Coleman

Attorney

UNITED STATES PATENT OFFICE.

LOUIS B. HALLIDAY, OF CINCINNATI, OHIO.

GAME APPARATUS.

Application filed November 11, 1924. Serial No. 749,252.

To all whom it may concern:

Be it known that I, LOUIS B. HALLIDAY, a citizen of the United States, residing at Cincinnati, in the county of Hamilton and State of Ohio, have invented certain new and useful Improvements in Game Apparatus, of which the following is a specification, reference being had to the accompanying drawings.

- 10 This invention relates to certain improvements in game apparatus and has relation more particularly to a device of this general character wherein surface projectiles are employed, and it is an object of the invention to provide a novel and improved apparatus of this kind wherein a certain degree of skill is required in playing the same yet at the same time affording amusement to the players.
- 15 Another object of the invention is to provide a novel and improved device of this general character comprising a plurality of indicators of different valuations, each of which being normally maintained in one position by a trip mechanism adapted to be released by the impact of the surface projectile to permit the indicator to assume a second or scoring position.

20 The invention consists in the details of construction and in the combination and arrangement of the several parts of my improved game apparatus whereby certain important advantages are attained and the device rendered simpler, less expensive and otherwise more convenient and advantageous for use, as will be hereinafter more fully set forth.

25 The novel features of my invention will hereinafter be definitely claimed.

30 In order that my invention may be better understood, I will now proceed to describe the same with reference to the accompanying drawings, wherein:

35 Figure 1 is a view in perspective illustrating a game apparatus constructed in accordance with an embodiment of my invention;

40 Figure 2 is a fragmentary vertical sectional view taken through the rear end portion of the apparatus;

45 Figure 3 is a view somewhat similar to Figure 2 but showing the indicator in its raised or scoring position;

50 Figure 4 is a fragmentary sectional view

taken substantially on the line 4—4 of Figure 2;

55 Figure 5 is a fragmentary view in top plan of the board proper, the indicating or scoring mechanism being omitted.

60 As disclosed in the accompanying drawings, 1 denotes a board of requisite dimensions having its upper surface flat and unobstructed except along a longitudinal marginal portion of which is provided a groove 2 affording a return runway for the projectiles. The side marginal portions of the board 1 are provided with the side walls 3 extending thereabove and also extending beyond the opposite ends of the board. The extremities of the side boards 2 are connected by the end walls 4 and 5. The space between the front end wall and the adjacent end of the board 1 is bridged by a plate 6 which underlies said wall 4 and board 1 to provide a pocket 7 to contain the projectiles 8 to be played. The space between the end wall 5 and the adjacent or rear end of the board 1 is also connected by the plate 9 underlying the same to provide a pocket 10 to receive the projectiles 8 after being played.

70 The rear end portion of the board 1 has its central portion cut out, as at 11, said cut out portion extending a material distance across the board 1 and providing a pocket 12 of increased size and particularly to assure requisite clearance for the projectiles as will hereinafter be more particularly referred to.

75 Resting upon the rear portion of the board 1 as an upstanding housing H positioned above the cut out portion 11 and having its bottom open with its rear wall 12 terminating at a desired point above the side walls 3. The lower marginal portion of the front wall 14 of the housing H is provided with a series of equally spaced and upstanding recesses 15 providing entrance openings for the projectiles 8.

80 The end walls 16 of the housing H support and have interposed therebetween a pair of vertically spaced parallel channel members or beams 17 through which are slidably disposed the vertically directed stems 18, said stems being also slidably disposed through the top wall 19 of the housing H. The stems 18 are of a number equal to the number of entrance openings 15 and each

2
of said openings 15 has a stem 18 positioned directly therebehind. Each of the rods 18 is constantly urged upwardly by a coil spring 20 surrounding the same and interposed between the upper member or beam 17 and a stop 21 carried by the rod 18. The stop 21 as herein disclosed comprises a washer surrounding the stem 18 and abutting a pin 22 disposed transversely through the stem 8, 10 said pin 22 is adapted to have contact with the top wall 19 of the housing H to limit the upward movement of the rod 18 under the influence of the spring 20.

Each of the rods 18 at a predetermined point above its lower end is provided in its forward marginal portion with a notch 23 to provide a catch 24 with which is adapted to be engaged a swinging latch 25 whereby the rod 18 is held in its lowered position 20 and against the tension of the spring 20. The latch 25 as herein disclosed is pivotally mounted upon a rod 26 supported by and bridging the space between the end walls 16 whereby the latch has its requisite swinging 25 movement in a vertical direction. The latch 25 above its pivot is provided with an upwardly extending arm 27 terminating in a hook 28 with which is engaged one end portion of a retractile spring 29 the opposite 30 end portion of which being anchored, as at 30, to the top wall 19 of the housing H. This spring 29 operates to constantly urge the latch 25 toward the rod 18 so that upon proper depression of the rod 18 the latch 35 25 will automatically engage the catch 24 and hold the rod 18 depressed.

The pivoted portion of the latch 25 is also provided with a depending arm 31 positioned directly behind an opening 15 and 40 which is adapted to be struck by a projectile entering the housing through such opening 15 and if the impact against the arm 31 is of sufficient force the latch 25 will be disengaged from the catch 24 to permit the rod 45 18 to be moved to its uppermost position.

The upper and exterior end portion of each of the rods 18, as herein disclosed, is provided with a spherical head 32 the front and rear face portions of which being 50 provided with value indications 33. When the rod 18 is depressed, the head 32 is substantially concealed behind an upstanding plate 34 substantially defining the forward marginal portion of the top wall 19 of the housing H and when said rod 18 is in its second 55 or uppermost position, said head is positioned above said plate 34 whereby the valuation 33 carried thereby may be readily observed by the player.

60 Disposed transversely across the top surface of the board 1 at a desired distance inwardly of the forward end thereof is a line 35. Secured to a side wall 16 of the housing H by a bracket 36 or the like is the 65 upper end portion of a downwardly and for-

wardly inclined chute 37 leading to the return groove 2 hereinbefore referred to.

My improved game may be played by any number of persons and I find that the interest in the game is materially increased by 70 first employing a spinner or its equivalent to be consequently employed by the players so that the player obtaining the lowest number or valuation will be designated as the game keeper and whose duties will be to return the various projectiles after played by the other persons, to keep the score, and otherwise supervise the game.

The game also preferably employs ten projectiles preferably marbles or kindred 80 spherical bodies and these marbles or the like are projected by a player toward the housing H with an endeavor to cause each of said projectiles to pass through an opening 15 with sufficient speed to strike an arm 85 31 with sufficient force to release a rod 18 so that he can have the benefit on his score of the valuation 33 designated on the head 32 carried by said rod. In the event a marble or projectile should fail to pass through 90 an opening 15 and should rebound forwardly of the line 35, the player can again employ such projectile but if it should stop inwardly of the line 35 such projectile is out of play 95 and will be picked up by the game keeper. After the ten projectiles 8 have been employed by a player his score is equal to the aggregate valuations of the released rods 18 and, of course, the player obtaining the highest score is declared the winner. As 100 each person finishes his play the game keeper returns the projectiles to the forward end portion or pocket 10 of the apparatus by placing such projectiles in the chute 37 said projectiles rolling down such chute and traversing the return groove 2.

The cut out portion 11 at the rear end portion of the board permits a projectile 8 to readily pass an arm 31 in the event the projectile should strike said arm with a force 110 insufficient to release the latch 25. It is also preferable that the cut out portion 11 be of a depth sufficient to permit the projectile to readily pass below the lower end of such arm.

115 It is also to be noted that all of the latches 25 are pivotally supported upon a common rod 26 and said latches are maintained in desired spaced relation by the spacing 120 sleeves 36.

125 From the foregoing description it is thought to be obvious that a game apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason 130

I do not wish to be understood as limiting myself to the precise arrangement and formation of the several parts herein shown in carrying out my invention in practice except 5 as hereinafter claimed.

I claim:

1. A game apparatus of the class described comprising a board adapted to be traversed by a projectile, a housing at one 10 end of the board having a forward wall provided with openings, movable indicating members supported by the housing, each of said members being positioned inwardly of an opening, means for normally urging each 15 of said members in one direction, and a latch mechanism for each of the members for holding the same when moved in the opposite direction, said latch mechanism being adapted to be released by the impact of a 20 projectile entering the housing, said end portion of the board being provided with a pocket extending inwardly of the housing below each of the latch mechanisms.

2. A game apparatus of the class described comprising a board adapted to be traversed by a projectile, a housing mounted upon one end portion of the board and having a front wall provided with openings through each of which a projectile is adapted 25 to enter the housing, vertically movable rods supported by the housing and extending therein, said rods being provided with value indicating means, each of said rods being provided with a catch, a latch for each 30 of the rods and engaging the catch of the rod when the rod is in one position, means for moving said rod to a second position when the latch is released, said latch being provided with an arm operating upon requisite impact by a projectile to disengage 35 the latch from its catch.

3. A game apparatus of the class described comprising a board adapted to be traversed by a projectile, a housing mounted 40 upon one end portion of the board and hav-

ing a front wall provided with openings through each of which a projectile is adapted to enter the housing, vertically movable rods supported by the housing and extending therein, said rods being provided with 50 value indicating means, each of said rods being provided with a catch, a latch for each of the rods and engaging the catch of the rod when the rod is in one position, means for moving said rod to a second position when the latch is released, said latch being provided with an arm operating upon requisite impact by a projectile to disengage 55 the latch from its catch, said latch being provided with a second outstanding arm, and a spring engaged with said second arm and a wall of the housing for constantly urging the latch toward its rod.

4. A game apparatus of the class described comprising a board adapted to be 60 traversed by a projectile, a housing mounted upon one end portion of the board and having a front wall provided with openings through each of which a projectile is adapted to enter the housing, vertically movable rods supported by the housing and extending therein, said rods being provided with 65 value indicating means, each of said rods being provided with a catch, a latch for each of the rods and engaging the catch of the rod when the rod is in one position, means for moving said rod to a second position when the latch is released, said latch being provided with an arm operating upon requisite impact by a projectile to disengage 70 the latch from its catch, said rods extending exteriorly of the housing, the value indicating means being carried by said extended portions, and means for substantially concealing said value indicating means 75 when the rods are held by the latches.

In testimony whereof I hereunto affix my signature.

LOUIS B. HALLIDAY.
